UNITED STATES PATENT OFFICE

CLAMENT A. SAVARIA, OF WORCESTER, MASSACHUSETTS

DESIGN FOR A GUARD PLATE FOR AUTOMOBILE DOOR

Application filed July 27, 1929. Serial No. 32,227. Term of patent 3½ years.

To all whom it may concern:

Be it known that I, CLAMENT A. SAVARIA, a citizen of Canada, residing at Worcester, in the county of Worcester and State of Massachusetts, have invented a new, original, and ornamental Design for Guard Plate for Automobile Door, of which the following is a specification, reference being had to the ac-

companying drawings, forming part thereof.

Fig. 1 is a perspective view of a guard plate showing my new design, and

Fig. 2 is an end elevation thereof.

I claim:

The ornamental design for a guard plate for automobile door as shown.

CLAMENT A. SAVARIA.
